UNITED STATES PATENT OFFICE.

CHAUNCY L. CROWELL, OF PEORIA, ILLINOIS.

HORSE-DETACHER.

SPECIFICATION forming part of Letters Patent No. 292,208, dated January 22, 1884.

Application filed October 31, 1883. (No model.)

To all whom it may concern:

Be it known that I, CHAUNCY L. CROWELL, of Peoria, in the county of Peoria and State of Illinois, have invented an Improved Horse-5 Detaching Device; and I do hereby declare that the following is a full, clear, and exact description thereof, reference being had to the annexed drawings, making a part of this specification, in which like letters of reference refer 10 to like parts, and in which—

Figure 1 represents a perspective view of the same; Fig. 2, a longitudinal section of the single-tree hook; Fig. 3, a perspective view of the holdback-hook.

15 The object of this invention is the construction of single-tree and holdback-hooks that may be readily detached from the traces and holdback-straps by the occupants of the carriage while in motion.

20 In the drawings, D represents the single-tree hook, capable of detachment from the traces by means of a cord or strap, D', running therefrom to within easy reach of the occupants of the carriage, and C is one of the 25 holdback-hooks, so designed as to automatically release the holdback-strap therefrom when the horse leaves the shafts of the carriage.

A is one of the shafts; B, the cross-bar; R, 30 the single-tree. Upon each end of the single-tree R is a strong metal ferrule, E, at the outer end of which is a hook, E'. A cylindrical hole, F', is bored into each end of the single-tree, and a coiled spring, S, and a small rod, 35 F, inserted into each of said holes F'. As the ends of the single-tree are both alike, I will limit my description to one alone. As shown in Fig. 2, the rod F is impressed by the 40 spring S against the inner face of the hook E'. Projecting upward and partially backward from the ferrule E is a hollow boss, E², within and at the upper end of which is pivoted the angle-iron N N'. The arm N' of this angle-iron projects downward into a slot cut 45 through the rod F, while the other end, N, extends approximately horizontally for a short distance, and is furnished with a strap or cord, D'.

In using my single-tree hook, when it is desired to attach the trace thereto, I pull the

end N³ of the angle-iron N N' away from the single-tree, and its end N' consequently presses the rod F against the spring S away from the hook E'. When the said rod F has been sufficiently retracted, the punctured end of the 55 trace is put between said rod and the hook E', and the angle-iron N released. The spring S then forces the end of the rod F back into the opening of the trace and against the hook E'. The traces are in this way most securely held 60 to the single-tree, and can be in no way released therefrom except by raising the arm N. To detach the traces from the hooks D all that we have to do is to move upward the arms N of the angle-irons N N', and the traces immediately drop out therefrom. We can operate these angle-irons either by clasping directly the arms N with the hands, or by pulling the 65 cords or straps D'.

Since the horse is secured to the shafts by 70 means of the holdback-straps, as well as by the traces to the single-tree, it is not sufficient to make the traces alone detachable by the occupants when there is danger of a run-away, for there would still be the holdbacks binding 75 the carriage to the horse. I therefore construct the holdback-hooks C as shown in Fig. 3. This consists of a hook, C, cast as a part of the standard C', by which it can be screwed to the upper side of the shaft A. To 80 this same standard, at M', is pivoted the curved shank M', at the other end of which is the hook M. Said hook is arranged in such a way as to permit its being dropped down in front of the convex face of the hook C, or to be 85 raised up and back away therefrom. In using this hook, the loop of the holdback-strap is put into the hook M, the same being raised away from the hook C, and brought downward. As the said strap is thus lowered, its 90 loop encircles the hook C, by which it is held. Said loop of the strap, resting upon the under part of the hook M, retains the same in such position. When, however, the horse is freed from the single-tree and advances away therefrom, the holdback-strap is pulled forward, the hook M raises it up and free of the hook C, it slides from said hook M, and the horse 95 is entirely detached from the carriage.

What I claim as my invention is as follows: 100

In a horse-detaching device of that kind in which there is a cylindrical opening, F', ferrule E, having hook E', and a rod, F, at each end of the single-tree thereof, as shown, the 5 combination, with such a single-tree, ferrule, and hook, of hollow boss E², formed as a part of said ferrule, the angle-iron N N', pivoted to and in the same, and the rod F, having a slot therein, as and for the purpose set forth.

In testimony that I claim the foregoing invention I have hereunto set my hand this 22d day of October, 1883.

CHAUNCY L. CROWELL.
